(57) **CLAIM**

The ornamental design for a balanced small basket shopping cart, as shown and described.

DESCRIPTION

FIG. 1 is a side elevation view of a balanced small basket shopping cart showing my new design;
FIG. 2 is a top plan view thereof;
FIG. 3 is a bottom plan view thereof;
FIG. 4 is a front elevation view thereof;
FIG. 5 is a rear elevation view thereof; and,
FIG. 6 is a front perspective view thereof, the broken line illustration of a bag and a shopping basket are for illustrative purposes only and form no part of the claimed design.
